Fig. 4

The side and end of the light fixture not illustrated in the drawing is identical to the side and end illustrated respectively by FIGURES 2 and 3, and the bottom is devoid of ornamental design.

I claim:

The ornamental design for a light fixture, substantially as shown and described.
